UNITED STATES PATENT OFFICE.

JAMES G. NOLEN, OF CHICAGO, ILLINOIS, ASSIGNOR TO JOHN E. SHEPHERD, OF CHICAGO, ILLINOIS.

COMBINED TELEPHONE AND PROTECTIVE ALARM SYSTEM.

944,575.

Specification of Letters Patent. Patented Dec. 28, 1909.

Application filed February 26, 1906. Serial No. 302,838.

To all whom it may concern:

Be it known that I, JAMES G. NOLEN, a citizen of the United States, residing at Chicago, in the county of Cook and State of Illinois, have invented certain new and useful Improvements in Combined Telephone and Protective Alarm Systems, of which the following is a specification.

My invention relates to improvements in combined telephone and protective alarm systems, and has for its primary object to provide simple and inexpensive means for establishing through the ordinary telephone system an efficient protective supervisory service, in the nature of burglar alarm, fire alarm, or like service.

More specifically one of the salient objects of my invention is to provide means whereby the ordinary bell and transmitter of a subscriber's telephone installation, and the line signal at the central station may effectively be employed as media for transmitting to the central station an unmistakable alarm upon the occurrence in the protected area of the conditions against which the service is provided for protection.

Another object of my invention is to provide means for insuring the continuous ringing of the telephone bell, until manually stopped, by the occurrence of such conditions within the protected area.

Another salient object of my invention is to provide a simple and efficient means for testing the condition of the protected circuit without disturbing the central operator upon the telephone line. And yet a further object of my invention is to provide appliances for effecting the protection described, which may be readily and cheaply applied to the ordinary commercial telephone system without change in the latter and with a minimum of expense.

Still other and further objects of my invention will best become apparent to those skilled in the art from the following description taken in conjunction with the accompanying drawings, wherein I have illustrated for purposes of a full disclosure an application of my invention to a well known form of telephone equipment, the parts being diagrammatically shown in a single view.

In the drawing C indicates in general a central station and S indicates in general

a subscriber's station, the two being shown as connected by a metallic circuit telephone line of the central energy type. It will be understood, however, that while for convenience this particular type of telephone system will be described in some detail, I do not limit my invention thereto, as it will be apparent to those skilled in the art that my invention might readily be adapted to other types of telephone equipment.

At the central station are provided in general a central battery CB, line signal appliances L, a combined ringing and listening key K, an operator's set O and a ringing generator R. These parts may be of any usual or preferred form, and the circuit may be run in any usual way, the circuit herein shown comprising a line wire 1, leading through the coil l of the relay of the signal appliances L to the subscriber's station, and a line wire 2 leading from the opposite side of the battery to the subscriber's station S.

The line signal appliances comprise a relay the armature l' whereof has its pivot end connected with the line 1 and adapted when attracted by the magnet l to close contact with the contact l' connected by wire l' through a series lamp l' with the wire 2.

As to the illustrated key K; in the line wire 1 are included a pair of normally closed switch tongues k¹, k², the spring k¹ being movable upon the rocking of the movable element k of the key, to break contact with the spring k² and make contact with the spring k³. The latter is connected by wire 3 with one terminal of the ringing generator R, the said terminal of said generator being preferably grounded by wire 4. The line wire 2 also includes a pair of normally closed springs k⁴, k⁵, the spring k⁴ being adapted to be moved by the rocking key member k to make contact with a normally open spring k⁶ which is connected by wire 5 with the ungrounded terminal of the ringing generator R. Upon the opposite side of the key member k are arranged two pairs of normally open contact springs adapted to be respectively closed by the key member k when rocked in a proper direction, a spring k⁷ of one of such pairs being connected by wire 6 with the line wire 1 (at spring k²) and the corresponding spring k⁸ of the other pair being connected by wire 7 with the line

wire 2 (at spring k^4). The remaining springs k^8 and k^{10} of the two pairs are connected to a wire 8 which includes therein primary winding i of an induction coil I, the operator's transmitter o t and the local battery l b constituting part of the subscriber's set. The secondary winding i' of coil I and operator's receiver o r are connected in closed circuit by wire 9 in the

10 usual manner. These parts may constitute part of an ordinary central station equipment and it will be obvious that under normal conditions the two line wires 1 and 2 have through connection through the springs of 15 the key K, and that if the key member k be rocked in one direction it bridges the ringing generator R upon the line, while if rocked in the other direction it bridges the operator's set across the line.

20 At the subscriber's station S the line 1 is led through the primary coil j of the induction coil J and the transmitter T to the upper contact s' of a switch hook s the pivot end whereof is connected to the line 2.

25 The secondary j' of the induction coil J is connected in closed circuit with the receiver R. The lower contact s^2 of the switch hook is connected by wire 10 with the line 1, said wire 10 including an initiator of an aural alarm such as the magnet coil of an ordinary electric bell B and a condenser 11. The parts constitute an ordinary subscriber's equipment.

30 The operation of the telephone installation under ordinary conditions will be readily understood by those skilled in the art and need not be described.

35 The protective circuit constituting part of my invention comprises parallel wires 12 and 13, between which are bridged normally open circuit closers 14, 14' which may be burglar alarm devices attached to doors and windows thermostats, for indicating an undue degree of heat in the premises, or other protective devices. It will be understood

40 that upon the occurrence of the conditions against which the system is designed for protection, the circuit closers are closed, but normally they stand open. The line wire 45 13 is led through the coil d of a drop D and is connected to the wire 10 between the bell B and the condenser 11. The drop D has a shutter d' controlled by an armature d^2 , which when attracted releases the shutter

50 which falls against the back contact d^3 . The shutter d' is connected to the wire 13, while its back contact is connected by wire 15 with the ground.

55 The wire 12 is, when the system is in working condition connected by wire 16 with the line wire 1 between the switch contact and the transmitter T. Such connection is preferably controlled by a switch U the pivot post of which is preferably con-

nected with line wire 12 and the blade of 65 which is adapted to swing into contact with the terminal contact u of wire 16, or a contact u' connected by wire 17 with the ground.

At the central station a condenser 18 is preferably provided, and connected between 70 the ungrounded terminal of the generator and the line wire 2 by wire 19.

75 It will now be seen that the protective system comprises normally open protective circuit closers and a circuit normally open at 80 said circuit closers which otherwise bridges the opening in the transmitter circuit between contact s' and switch hook s , such bridging connection comprising wire 16, blade of switch U, wire 12, a circuit closer 85 14 or 14', wire 13 and part of wire 10 to the switch hook s . This connection also, it will be apparent, closes (except for the normal opening at the circuit closer 14) a circuit including the line signal and a source of current supply, such circuit being traced from central battery C B by wire 1 through the relay coil of the line signal, through the primary j of the induction coil J, the transmitter T, wires 16, 12, 14 and 13, 10 and 2 back 90 to the central battery.

95 The operation of the parts will be as follows: Assuming that switch U be thrown to make contact with point u , when a circuit closer in a protective circuit is closed, the circuit last traced is closed so that the relay of line signal equipment is energized attracting its armature l' and closing the local circuit l^3 , so that the line signal lamp l^4 is energized and the operator's attention attracted. Instantly upon the closing of the circuit described the coil d of drop D becomes energized so that its shutter d' falls against the contact d^3 establishing a ground. Now the constantly running generator R 105 transmits its impulses through the wires 4, 19, 2, switch hook s , contact s^2 , wire 10, alarm bell B, wire 13, shutter d' and wire 15 to ground so keeping the bell B constantly ringing even though the circuit closer has 110 been opened instantly after its first closing, as by the withdrawal of the burglar or his closing of the window or door, the opening of which initiated the signal.

115 It will be understood that as usual in telephone equipments the bell or other aural alarm will be within effective distance of the transmitter T to communicate sound vibrations to the said transmitter, and, it being remembered that the closing of the 120 circuit closer 14 or 14' automatically bridges the opening of the transmitter circuit at the switch hook, it will be apparent that when the operator depresses the key member k to bridge in her telephone set, in response to 125 the lighting of the line signal lamp l^4 she hears a continuous ringing of the bell at the subscriber's station, and is thereby instantly

5 apprised of the existence of trouble in the protective circuit, as under normal conditions the bell and transmitter are never in circuit at the same time, as will be well understood by those skilled in the art.

It will, of course, be apparent that in adapting my system to party lines it is well to use bells of different tones, or having other distinguishing characteristics, to distinguish between the different subscribers' stations on the line.

For purposes of testing the condition of the systems and ascertaining that no doors or windows are open in the protected area 15 but that the circuit closers are all open, the switch U is thrown over upon contact u' . Assuming one of the circuit closers to be closed, this establishes a ground circuit from ground wire 4 to generator R, by wire 19, to 20 wire 2, thence through the switch hook, wire 10, including bell B, wire 13, circuit closer, wire 12, switch U and wire 17 to ground, so occasioning the bell to ring. This circuit, it will be observed does not include the line 25 signal and in no way disturbs the operator at "central". If, however, all of the circuit closers are in proper normal condition—that is to say, open—the circuit is not completed and no response is given by the bell.

30 It will now be seen that my invention provides for the calling of the central operator upon the closure of a circuit closer in a protective circuit; for the initiation of an audible signal upon the closing of the circuit closer and for a continuation of such signal when started irrespective of the subsequent opening of the circuit closer, such a continuously sounding alarm tending to frighten away an intruder in the case of burglar 35 alarm, or to notify the occupants of the protected area in case of fire, and also to notify the central operator instantly of the existence of undue conditions by the ringing of the telephone bell heard in the transmitter. As a further refinement, I place in series in the protected circuit a line breaking switch w which may be operated by a key w' , to open the circuit. This switch may conveniently be placed in the barrel of the 40 door lock, so that when the key is inserted in the open door the protection system is disabled. Thus an authorized person may enter the premises without sounding an alarm, by inserting his key, opening the door, 45 throwing switch U to open position, withdrawing his key, closing the door and throwing switch U back to contact with point u .

While I have herein described in some detail a specific embodiment of my invention 50 for purposes of a full disclosure, it will be understood that I do not intend to limit my invention to the specific arrangement shown, as it will be apparent to those skilled in the art that its parts might be variously ar-

ranged and constructed without departing 65 from the spirit and scope of my invention.

Having thus described my invention, what I claim and desire to secure by Letters Patent of the United States, is:

1. The combination with a telephone system, involving a line connection from a central station to a subscriber's station, suitable means of current supply; at the central station an operator's set and a line signal, and at the subscriber's station a transmitter and a switch opening the transmitter circuit when the subscriber's line is not in use, of a protective system comprising a normally open protective circuit closer, a circuit normally open at said circuit closer and otherwise bridging the open switch connection of the transmitter, and otherwise closing a circuit including the transmitter the line signal and a source of current supply, and an electrically initiated aural alarm 85 device having its electro-responsive part operatively associated with the circuit closable by the protective circuit closer and energized by a central source of supply.

2. The combination with a telephone system, involving a line connection from the central station to a subscriber's station, suitable means of current supply; at the central station an operator's set and a line signal, and at the subscriber's station a transmitter 90 and a switch opening the transmitter circuit when the subscriber's line is not in use; of a protective system comprising a normally open protective circuit closer, a circuit normally open at said circuit closer, and otherwise closing the circuit including the line signal and a source of current supply, an audible alarm device within effective distance of the transmitter, having an electro-responsive controlling part operatively associated with the protective circuit to initiate the activity of the alarm device, and means, responsive to the closing of the protective circuit, for closing an energized circuit excluding the said circuit closer and 100 including the alarm device.

3. The combination with a telephone system, involving a line connection from the central station to a subscriber's station, suitable means of current supply; at the central station an operator's set and line signal appliances, and at the subscriber's station a transmitter and a switch opening the transmitter circuit when the subscriber's line is not in use; of a protective system comprising a normally open protective circuit closer, a circuit normally open at said circuit closer and otherwise bridging the open switch connection of the transmitter, and otherwise closing a circuit operatively including the line signal appliances and a source of current supply; an electric audible alarm within effective distance of the telephone trans-

mitter, and means responsive to the operation of the circuit closer to initiate the operation of the alarm, arranged to permit the continued operation of said alarm independently of the condition of the protective circuit closer.

4. The combination with a telephone system, involving a line connection from the central station to a subscriber's station; suitable means of current supply; at the central station an operator's set and line signal appliances, and at the subscriber's station a transmitter and a switch opening the transmitter circuit when the subscriber's line is not in use; of a protective system comprising a normally open protective circuit closer, a circuit normally open at said circuit closer and otherwise bridging the open switch connections of the transmitter, and otherwise closing a circuit operatively including the line signal appliances, and a source of current supply; an electric audible alarm within effective distance of the transmitter, and means for automatically closing another energized circuit including said alarm device, operable upon the closing of said circuit closer.

5. In a system of the character described, the combination with a telephone system involving a line, a source of current supply therefor, and a ringing generator normally connected to said line, of an audible electro-responsive alarm device at the subscriber's station, and at the subscriber's station means for establishing a circuit including the ringing generator and the audible alarm device, such means including a protective circuit and a normally open protective circuit closer.

6. In a system of the character described, the combination with a telephone system involving a line connection, at the central station line signal apparatus, an operator's set and a ringing generator; at the subscriber's station a transmitter and means for opening the transmitter circuit when the set is not in use, protective circuit closers, connections arranged to establish a circuit closable by said circuit closers, including a source of current supply, the operating portion of the line signal apparatus at central station and the subscriber's transmitter; an electro-responsive audible alarm device in the said circuit within effective distance of the transmitter; and means in said circuit for establishing a grounded circuit including the ringing generator and the audible alarm device, upon the closing of the protective circuit, whereby an audible signal is initiated upon the closing of the protective circuit, and is thereafter maintained irrespective of the condition of the protective circuit.

7. In combination with a telephone system involving a line connection, a central station equipment comprising a normally operating

grounded ringing generator; and at a subscriber's station an audible electro-responsive alarm device, suitable circuit connections, a normally open circuit closer, adapted when closed to establish a circuit including a source of energy, and in said circuit an automatic circuit closer operable by the aforesaid closing of said circuit to establish a ground circuit including the central ringing generator and the subscriber's alarm device.

8. The combination with a telephone system involving suitable circuit connections, at central an operator's set, a line signal, independent sources of current supply for the line signal and alarm devices, and at the subscriber's station a transmitter, a switch for opening the transmitter circuit, and an alarm, of a protective circuit, and protective devices therein, arranged when operated to effect the establishment of a circuit for the line signal and its source of supply, including the transmitter, and another circuit for the alarm and its source of supply.

9. The combination with a telephone system involving suitable circuit connections; at central station an operator's set, a line signal, independent sources of current supply for the line signal and alarm devices, and at the subscriber's station a transmitter, a switch for opening the transmitter circuit, and an alarm, of a protective circuit, protective devices therein arranged when operated to effect the establishment of a circuit for the line signal and its source of supply including the transmitter and another circuit for the alarm and its source of supply, and a test switch adapted when in one position to condition the protective devices to establish a circuit for the alarm and its source of current without affecting the line signal.

10. The combination with a telephone system involving at the subscriber's station a telephone set including a telephone call bell and a transmitter within effective distance of the call bell, and at central station an operator's equipment; of a protective system involving means for contemporaneously establishing an operating circuit for the said call bell and a talking circuit for said transmitter.

11. The combination with a telephone system involving at the subscriber's station a telephone set including a transmitter, a call bell and a switch normally connected with the call bell and opening the transmitter circuit, and at the central station involving means of current supply for the call bell, of a protective circuit involving means for closing the circuit of the transmitter, and a circuit for the call bell and the central source of current supply.

12. The combination with a telephone system having a source of current supply, and

comprising at the subscriber's station a transmitter and a switch normally opening the transmitter circuit, of a sounding alarm, within effective distance of the transmitter,

5 a normally open circuit arranged to be energized, when closed, by the source of current supply for the telephone system, and means responsive to closure of said circuit for establishing a bridge across the switch-opening in

the transmitter circuit and initiating the 10 operation of the sounding alarm.

In testimony whereof I hereunto set my hand in the presence of two witnesses.

JAMES G. NOLEN.
